UNITED STATES PATENT OFFICE.

PAUL R. FINCH, OF DES MOINES, IOWA.

GAS-MANTLE.

No. 870,229.

Specification of Letters Patent.

Patented Nov. 5, 1907.

Application filed August 10, 1907. Serial No. 387,985.

To all whom it may concern:

Be it known that I, PAUL R. FINCH, a citizen of the United States, residing in Des Moines, county of Polk, and State of Iowa, have invented a new and useful 5 Improvement in Gas-Mantles, of which the following is a specification.

The object of my invention is to provide a mantle for inverted gas lamps which will be simple, strong, durable and inexpensive in construction and which 10 will be adapted to produce a greater degree of light from a small supply of heat than any of the mantles now in use.

A further object is to provide a mantle wherein the same will be seamless at the extremity of its base thus 15 doing away with the central opening and tying cord usually employed in forming the base of inverted mantles.

My invention consists of certain details of construction hereinafter set forth, pointed out in my claims 20 and illustrated in the accompanying drawings in which

Figure I shows an inverted plan view of my device; Fig. II shows a perspective view of my device; and, Fig. III shows a second perspective view of the same.

Referring to the accompanying drawings the reference numeral 10 is used to indicate the mantle holder 25 provided with its supporting lugs 11 and the numeral 12 indicates the mantle proper which is commonly called the web.

The numeral 13 indicates a longitudinal seam located on one side of the web said seam branching into 30 two seams 14 and 15 at a point near the hemi-spherical base of the mantle. Directly opposite to the seam 13 and located longitudinally in the mantle 12 is a second seam 16, exactly similar in every respect to the seam 13, and branching near the base of the mantle into two seams 17 and 18. The extremity of the base of the mantle is absolutely seamless and the object of the longitudinal seams 13 and 16 and their respective branches is to produce the curved base in the bag so

that when the mantle is properly treated with the necessary chemicals and secured to the holder 10, it will be provided with an even, regular and symmetrically curved base void of seams at its extremity. The mantle 12 is secured to the holder 10 in the usual manner as shown at 19. It is obvious that by this construction an even and symmetrical mantle simple, durable and inexpensive in construction will be produced. The seams 13 and 16 and their respective branches are produced in the bag by a knitting process thus obviously causing them to be small and neat 50 and not presenting a thickness much greater than the bag itself and causing very little if any added obstruction to the flow of light.

Different styles of this class of mantles in which the side seams are employed may be produced without changing my invention, the principal feature of which is to produce the seamless base extremity and thus provide an evenness of the mantle bag with no added obstruction to the flow of light at any particular spot.

Having thus described my invention what I claim 60 and desire to secure by Letters Patent of the United States is:

1. A gas mantle embodying a cylindrical web having a hemi-spherical base formed evenly and symmetrically, a pair of oppositely disposed longitudinal seams extending 65 through the top of said web and terminating at points away from the extremity of the base thereof, and two divergent branches extending from the lower end of each seam to extend on the outer portions of the base extremity.

2. A gas mantle embodying a cylindrical web having a hemi-spherical base, said web being divided in its body into two parts by a pair of straight seams and adjacent the extremity of the hemi-spherical base having its line of division extending in curved paths so as to be on the outer 75 portions of the extremity of the hemi-spherical base.

PAUL R. FINCH.
